AIR CONDITIONER

Ray C. Sandin, Winnetka, and Jon F. Morgan, Glen Ellyn, Ill., assignors to General Electric Company, a corporation of New York

Filed Sept. 27, 1963, Ser. No. 76,764

Term of patent 14 years

(Cl. D62—4)

FIG. 1 is a top front perspective view of an air conditioner showing our new design;

FIG. 2 is a fragmentary side elevation partly in section;

FIG. 3 is a section on line 3—3 of FIG. 1 with portions omitted for ease of illustration.

Each end elevation is identical.

The dominant features of our design reside in the portions shown in full lines.

We claim:

The ornamental design for an air conditioner, substantially as shown and described.
